(57) **CLAIM**

(21) Appl. No.: **29/316,086**

The ornamental design for a device for cleaning HVAC coils,
as shown and described.

(22) Filed: **Aug. 21, 2009**

DESCRIPTION

(51) LOC (9) Cl. **08-99**

FIG. 1 is a perspective view of device for cleaning HVAC
coils, showing my new design;

(52) U.S. Cl. **D32/35; D23/213**

FIG. 2 is a front side elevation view thereof;

(58) Field of Classification Search D23/213,
D23/223; D32/35; 239/273, 279, 566, 337;
134/172

FIG. 3 is a rear side elevation view thereof;

See application file for complete search history.

FIG. 4 is a right side elevation view thereof;

(56) **References Cited**

FIG. 5 is a left side elevation view thereof; and,

U.S. PATENT DOCUMENTS

FIG. 6 is a plan view thereof.

3,844,449 A * 10/1974 Alter 222/175
5,100,058 A * 3/1992 Wei 239/273
